Primary Examiner — Martie K Holtje*(74) Attorney, Agent, or Firm* — Banner & Witcoff, Ltd.(57) **CLAIM**

The ornamental design for an electronic dog collar, as shown and described.

DESCRIPTION

FIG. 1 is a front perspective view of an electronic dog collar showing the new design;

FIG. 2 is a front view thereof;

FIG. 3 is a right side view thereof;

FIG. 4 is a left side view thereof;

FIG. 5 is a top view thereof; and,

FIG. 6 is a bottom view thereof.

The broken line showing of the remainder of the electronic dog collar is for environmental purposes only and forms no part of the claimed design.

1 Claim, 5 Drawing Sheets(56)
